US00D803170S

(12) **United States Design Patent** (10) **Patent No.:** **US D803,170 S**
(45) **Date of Patent:** **** Nov. 21, 2017**

(54) **LIGHT-EMITTING DIODE**

(71) Applicants: **CITIZEN ELECTRONICS CO., LTD.**, Yamanashi-ken (JP); **CITIZEN WATCH CO., LTD.**, Tokyo (JP)

(72) Inventors: **Yasuaki Kayanuma**, Yamanashi-ken (JP); **Tatsuro Yamada**, Yamanashi-ken (JP); **Yuki Nishikawa**, Shiga-ken (JP); **Yuki Ochiai**, Yamanashi-ken (JP)

(73) Assignees: **CITIZEN ELECTRONICS CO., LTD.**, Yamanashi-Ken (JP); **CITIZEN WATCH CO., LTD.**, Tokyo (JP)

(**) Term: **15 Years**

(21) Appl. No.: **29/598,100**

(22) Filed: **Mar. 23, 2017**

(57) **CLAIM**

The ornamental design for a light-emitting diode, as shown and described.

DESCRIPTION

FIG. 1 is a top perspective view of a light-emitting diode showing an upper surface with front and left side surfaces; FIG. 2 is a bottom perspective view thereof showing a bottom surface with rear and right side surfaces; FIG. 3 is a front view thereof, a rear view being identical to FIG. 3;

FIG. 4 is a top plan view thereof;

FIG. 5 is a bottom plan view thereof; and,

FIG. 6 is a left side view thereof, a right side view being a mirror image of FIG. 6.

The broken lines shown herein are for illustrative purpose only and form no part of the claimed design.

1 Claim, 3 Drawing Sheets
